MODULATING AND AMPLIFYING SYSTEM

Warren H. Bliss, Brooklyn, N. Y., assignor to
Radio Corporation of America, a corporation of
Delaware

Application August 31, 1938, Serial No. 227,644

4 Claims. (Cl. 179—171.5)

This invention relates to systems for use in facsimile apparatus in the conversion of light of an image or subject of which the electro-optical representation is to be produced at receiving points into electric currents. The invention further relates to the means by which these produced electric currents are caused to energize a transmitter which is to distribute the produced energy either by radio or a wire line connecting channel to the appropriately selected receiving points.

In the conversion of record subjects with the usual form of facsimile apparatus the record is carried upon a scanning drum and is illuminated in a point to point manner from a suitable light source from which the light rays are directed by a suitable optical system through appropriately selected diaphragms to focus as a sharp point on the record subject. The light reflected from the record subject is then caused to enter give the photosensitive element of a photoelectrically active light translating element.

During the process of scanning relative motion is provided between the illuminating light source and the subject. This relative motion may come about, for example, by causing the drum carrying the record subject to rotate while the light spot is moved slowly longitudinally along the drum so that the record subject is traversed in a two-dimensional path by the light spot. Many other systems for causing a bi-dimensional analysis of the light values of the record subject are known and will not herein be considered, since the foregoing example may be taken as purely illustrative of this phase of the invention.

In the usual form of facsimile or picture transmitting system the amount of light available is of relatively low intensity value and, accordingly, the photoelectric currents resulting from translating the varying light values of the record subject into electric currents are also relatively low. Such low intensity electric currents require a substantial degree of amplification prior to the time when the transmitter is modulated if the depth of modulation is to be adequate or in case the signals are used by way of a wire line connecting channel to control directly a suitable recording device to reconstruct an electro-optical likeness of the record subject which initially causes the production of the electrical impulses, the electric impulses must be of relative great magnitude in order to produce satisfactory response of the recording means.

Accordingly, the present invention has as one of its primary objects that of providing greater ease in obtaining amplification of the

signals resulting from the relatively low light values while at the same time providing an amplification system wherein wave form distortion of the electrical energy will not result because of the high degrees of amplification required.

Other objects of the invention are to provide a facsimile transmitting system and the operational circuits for use in connection therewith which to a large extent make use of what is considered a novel manner of operating and connecting known elements so as to provide improved operation and higher degrees of efficiency in light translating operations.

Other objects and advantages will, of course, naturally become apparent and at once suggest themselves to those skilled in the art to which the invention is directed when the following specification and claims are read in connection with the accompanying drawing, wherein the single figure thereof illustrates, largely in diagrammatic manner, one of the several suitable forms which the invention may assume in practice.

Referring now to the drawing for a further understanding of the invention it will be seen that it comprises in its essential parts the use of suitable apparatus for directing light reflected from a subject or record carried upon a facsimile scanning drum upon an electronic light translating element (such as a form of photoelectric tube) from which electrons of a magnitude proportional to the intensity of illuminating light are released. Such a form of photoelectric tube may be one of the type already described by Zworykin and others and known as an "electronic multiplier tube" (see Proceedings of the Institute of Radio Engineers, March 1936, vol. 24, No. 3 at page 351 et seq.). The released electrons developed within a photoelectrically responsive tube of this type are, after a considerable number of stages of multiplication, caused to control a modulating circuit in which provision for compensating for non-linearities of the system is made.

Now making more specific reference to the accompanying drawing, a light beam 11 as reflected from the scanning drum in accordance with the above outlined description, is caused to fall upon or to be projected upon the light sensitive cathode or electrode element 13 of an electronic multiplier tube 15. One specific type of electronic multiplier tube which is suitable for this purpose may, for example, be a tube of the general type described and claimed in Zworykin and Massa Patent 2,078,304 granted April 27, 1937. It comprises a plurality of electrode elements 13,

17, 19 through 21, arranged on one side of the tube and immediately above these electrode elements are a plurality of "upper" or accelerating electrodes 22. The accelerating electrodes are connected, as shown, to the next succeeding lower electrode and are maintained at the same potential. The final collecting electrode 23 is located immediately adjacent the last impact member 21 and intermediate the collector and the final lower electrode 21 is a screening electrode 24 which is connected with the last upper plate electrode 22, all as described in the aforesaid Zworykin et al. application. For the purpose of concentrating the electrons flowing between the first lower electrode element 13 and the final collecting electrode element 23 there is provided a suitable magnetic field developed by way of the electromagnet 25 which is energized from a source of direct current supplied from terminals 26. The intensity of this electromagnetic field is controlled by means of the variable resistor 27. The magnetic field is arranged to become active transversely on the tube 15 as was described in the above named Zworykin et al. application.

Whenever light from the record drum passes along the path 11 to activate or energize the lower electrode 13, photoelectrons are released therefrom and these electrons, in effect, "bounce" from one to another of the lower electrode members 13, 17, 19 to 21 etc. until they are collected by the final collector electrode 23. This then results in a greatly magnified electron flow in the final output circuit due to the release of secondary electrons from each of the electrode members 17, 19-21 etc. so that the current flowing in the final stage is increased over that resulting from the initial release of photoelectrons from the electrode 13 by the secondary emission factor of the tube raised to a power corresponding to the number of impact stages.

The output from the system hereinabove described which is to be effective to control the modulator element may result from the voltage drop across a load resistor connected either to the final lower electrode element 21 or to the final collecting electrode 23, depending, of course, upon whether or not a control signal of positive or negative polarity, is desired. Therefore, connected to the final lower electrode element 21, there is provided a resistor element 28 and similarly, connected to the final collecting electrode 23 there is provided a resistor 29. These resistors have their lower ends connected to points on voltage dividers 30 and 31 respectively, and then to ground at 32.

The system in the form disclosed by the accompanying drawings is primarily designed for removing the signal from the multiplier tube across the resistor 28. For this purpose the voltage drop appearing across the resistor 28 is transferred by way of conductor 36 to the control electrode circuit of the modulators 37 and 38 so as to act upon these tubes in parallel. Where it is desired to use a control signal of the opposite polarity the control voltage for the modulators 37 and 38 may be derived after suitably changing the bias on the tubes and other working parameters of the system by connecting the conductor 35 to the input or control electrode of the modulators 37 and 38 so that there is supplied to these tubes the voltage drop appearing across the output resistor 29.

The tubes 37 and 38 are preferably of the pentode type and are so arranged that the voltage drop appearing across resistors 28 or 29, de-

pending upon which of the above described energizing paths for the modulators 37 and 38 is selected so as to energize the control grids of these tubes. The cathode elements of each of these 5 modulator tubes 37, 38 are grounded at 39, while there is supplied to the screen grid electrodes 40 and 41 respectively a tone frequency by way of the transformer 42.

The tone frequency input which is to be modulated by the output energy from the tube 15 is applied to the terminal points 43. This tone frequency energy is developed from any suitable source of oscillatory energy (not shown) and is supplied for the purpose of permitting the use 10 of a so-called A. C. amplifier in contrast to a straight D. C. amplifier. With the control energy from tube 15 applied to the control grid members of tubes 37 and 38 and the tone carrier supplied at the terminals 43 being fed from 15 terminals 43 through the transformer 42 so as to become active upon the screen grid electrodes 40 and 41 of the tubes 37 and 38, the tone carrier frequency will be modulated in well known manner. It is usually desirable that the tone frequency be supplied to the tubes 37 and 38 so that 20 these tubes operate as a balanced modulator. So connected, the secondary winding 44 of the transformer 42 is center-tapped at point 45 and this point connected by way of the conductor 46 to a suitable point on the voltage divider 31, as 25 indicated, to supply the proper voltage upon the screen grid electrode members. Anode voltage for the tubes 37 and 38 is supplied by connecting the conductor 47 to the righthand end of the 30 voltage divider 31 and to the source of positive potential. This conductor 47 then connects to the center-tap 48 of a potentiometer 49, having its outer ends connected to the anode elements of tubes 37 and 38 through the conductors 50 and 40 51. The potentiometer 49 serves to balance the system in known manner.

Output energy representing the amplified output from the tube 15 is then fed by way of the primary winding 52 of transformer 53 to the secondary winding 54 and thence caused to become effective upon the control electrode of a further 45 amplifying tube 55. This amplifier tube 55 has its anode voltage derived from the same source as the tubes 37 and 38 by way of a conductor 56 connected with the conductor 47 and to the primary winding 57 of the output transformer 58. There is also applied, however, to the amplifier 50 tube 55 and caused also to become effective in the control electrode circuit thereof a counter- 55 electromotive force derived from the carrier frequency input connected at the terminals 43 in order to improve the linearity of the system. This counter-electromotive force is developed across the potentiometer 59 and is variable in 60 its effect in accordance with the positioning of the slider contact 60 upon the potentiometer element 59. The slider contact 60 of the potentiometer connects to one side of a condenser 61, the other side of which is connected to the transformer secondary winding 54 so that there is applied in the control electrode circuit of the tube 55 a counter-electromotive force derived from the tone frequency input. This is the voltage 65 which is used to improve the linear characteristics of the overall modulator device. The potential drop developed across resistor 62 is also effective on the tube 55 by way of the connection of the control electrode circuit through resistor 62 and its connection to ground at 32. The 70 cathode element of the tube 55 is connected to

the ground point 32 by way of the usual shunt path comprising the cathode bias resistor 63 and condenser 64 and the amplified output energy from this tube is fed by way of the primary winding 57 of the transformer 58 to the secondary transformer winding 65. At the output terminals 66 the energy, as suitably amplified, may be used for the purpose of modulating the transmitter carrier or for keying with the carrier or, where desired, for controlling the operation of monitor equipment, or for the purpose of actuating directly, or through suitable amplifiers, suitable reproducing equipment by which replicas of the subject causing the initial photo-response in the tube 15 may be made. Since the characteristics of tubes 37 and 38 may not be identical the positive half of the modulating cycle might vary from the negative half of the cycle, thus resulting in non-linearity of modulation. The potentiometer arrangement 59, 60 is such that a part of the carrier cycle is emphasized with respect to the other part of the cycle. This means, then, that a signal having opposite distortion characteristics to that developed in tubes 37 and 38 will be fed across the resistor 62 connected serially with the transformer secondary 54, thus compensating for non-linearity in the modulating cycle.

While the present disclosure is not directed particularly to the exact form of transmitter which is to radiate the signal energy or to the wire-line connecting channels, which are to connect the amplifier 55 with suitable recording or monitoring apparatus, it is to be understood that this apparatus is of substantially standard form and does not per se form a part of the present invention. Any of the several well known forms of transmitter control may be utilized with the circuit and apparatus hereinabove described. Naturally, many and various modifications of the invention herein disclosed may be made without departing from the spirit and scope thereof and, therefore, I believe myself to be entitled to make and use any and all such modifications which fall fairly within the spirit and scope of what is hereinafter claimed as my invention.

What I claim is:

1. A transmission system comprising a plurality of modulator tubes each having a plurality of cold electrode elements, means for applying in parallel modulation signals to one cold electrode of each of the modulator tubes, a source of carrier frequency energy, means for applying said carrier frequency energy to a second cold electrode of said modulator tubes in push-pull whereby said modulation energy is adapted to modulate the produced carrier frequency energy, an output circuit for said modulator tubes, an amplifier connected to receive upon its input circuit carrier frequency signal modulated energy from the modulator stage, means for simultaneously applying to the input circuit of the amplifier a counter-electromotive force derived from the carrier frequency source serially with the signal modulated energy, for improving linearity of the system, and a load circuit connected to the output of the amplifier.

2. A transmission system comprising a plurality of modulator tubes each having an electron

emitter and a plurality of cold electrode elements, means for converting light energy into electrical energy and for applying the produced electrical energy as a modulation signal upon one cold electrode of each of the modulator tubes in parallel, a source of carrier frequency energy, means for applying said carrier frequency energy to a second cold electrode of each of said modulator tubes in phase opposition whereby said modulation energy is adapted to modulate the produced carrier frequency energy in each tube, an output circuit for receiving the modulated output from each of the modulator tubes, an amplifier connected to receive upon its input circuit carrier frequency signal modulated energy from each of the modulator tubes, means comprising a plurality of resistor and condenser elements for simultaneously applying to the input circuit of the amplifier a counter-electromotive force serially with the signal modulated energy derived from the carrier frequency source for improving linearity of the system, and a load circuit connected to the output of the amplifier.

3. A transmission system comprising a plurality of modulator tubes each having an electron emitter and a plurality of cold electrode elements, a photoelectrically responsive electron multiplier device for converting light energy into electrical energy and for applying the produced electrical energy as a modulation signal upon one cold electrode of each of the modulator tubes in parallel, a source of carrier frequency energy, means for applying said carrier frequency energy to a second cold electrode of each of said modulator tubes in phase opposition whereby said modulation energy is adapted to modulate the produced carrier frequency energy in each tube, an output circuit for receiving the modulated output from each of the modulator tubes, an amplifier connected to receive upon its input circuit carrier frequency signal modulated energy from each of the modulator tubes, means comprising a plurality of resistor and condenser elements for simultaneously applying to the input circuit of the amplifier a counter-electromotive force serially with the signal modulated energy derived from the carrier frequency source for improving linearity of the system, and a load circuit connected to the output of the amplifier.

4. A transmission system comprising means for developing electrical signals representative of intelligence, a balanced modulator, means for developing carrier frequency energy, means for simultaneously applying such carrier frequency energy and said signals representative of intelligence to said balanced modulator, an amplifying tube having anode, cathode and at least one control electrode, means coupling the control electrode of said thermionic tube to the output of said balanced modulator whereby energy from the output circuit of said balanced modulator is impressed onto the control electrode-cathode circuit of said thermionic tube, resistance means connected serially with said coupling means, a potentiometer, means for impressing a wave of the same frequency as said carrier current onto said potentiometer, and means coupling said potentiometer to said serially connected resistance.
